106,465

DESIGN FOR A BEDSPRING OR SIMILAR ARTICLE

Benjamin M. Frank, New York, N. Y., assignor
to Greenpoint Metal Bed Company, Inc.,
Brooklyn, N. Y.

Application July 7, 1936, Serial No. 63,695

Term of patent 14 years

To all whom it may concern:

Be it known that I, Benjamin M. Frank, a citizen of the United States, and residing at New York, in the county of New York and State of New York, have invented a new, original, and ornamental Design for a Bed Spring or Similar Article, of which the following is a specification, reference being had to the accompanying drawing, forming part thereof, and in which

Fig. 1 is a top plan view of a bed spring showing my new design, the top coil of each spring being shown in full lines and lower coils of the springs being indicated by dotted lines.

Fig. 2 is an elevation of slightly less than one-half of one end of the spring, the appearance of the unillustrated portion being substantially identical with that of the illustrated portion.

The characteristic feature of the present design resides in the squares formed by auxiliary springs extending transversely and longitudinally between the circular tops of main vertical coil springs and a series of elongated notched plates positioned with their long axes extending longitudinally of the spring, producing predominant longitudinally extending stripes and less dominant horizontal stripes between the rows of main coil springs. Within each square and positioned concentrically thereof are the tops of the main coil springs connected by auxiliary coil springs to the notched plates at the corners of the squares.

What is claimed is:

The ornamental design for a bed spring or similar article substantially as shown and described.

BENJAMIN M. FRANK.
